TELEPHONE SUBSTATION CIRCUIT

Raoul A. Faralla, Long Branch, N. J.

Application March 10, 1945, Serial No. 582,099

13 Claims. (Cl. 179—81)

(Granted under the act of March 3, 1883, as
amended April 30, 1928; 370 O. G. 757.)

1

The invention described herein may be manufactured and used by or for the Government for governmental purposes, without the payment to me of any royalty thereon.

This invention relates to substation telephone circuits, and, particularly, to portable field telephones and substation circuits which, because of the use to which they are subjected, may be connected to lines of greatly varied lengths.

It is well-known in the art that the sensitivity of the magnetic sound-powered receivers is superior to the sensitivity of the receivers of standard type, the output level of the sound-powered receivers being from 12 to 16 db. higher than of the electromagnetic receivers, and, therefore, it is especially desirable to use such receivers in connection with the field telephone substations, such as Army Signal Corps substations, since the superior sensitivity of such receivers makes it possible to extend the range of the field telephone communications. However, when receivers of this type become connected to lines of relatively short length, the intensity of the signal impressed upon them is so high that the output of the receiver becomes too loud, and, in extreme cases, the receiver becomes overloaded to such an extent that its articulation quality is impaired and the speech becomes almost unintelligible. Moreover, when sound-powered receivers are substituted for receivers of standard type, they reproduce cross-talk and noise signals with such a degree of loudness that the signal-to-noise ratio is impaired, and the cross-talk signal interferes with the desired speech signal. This disadvantage disappears when the sound-powered receiver is connected to long lines, because the noise and cross-talk signals become attenuated to such an extent that the receiver clearly reproduces only the desired signal.

In order to obtain the same degree of clarity of the desired signal when receivers of this type are connected to lines of short length, it becomes necessary to reduce their sensitivity, and the invention discloses several methods of accomplishing this result.

According to the disclosed methods, the number of effective turns of the coil of the receiver may be varied, thus decreasing the transmitting efficiency of the receiver, and, at the same time, creating the mismatched impedance condition in the substation circuit which, in itself, acts as a means for reducing the efficiency of the substation circuit. Mechanical means are provided for altering the connections in the substation circuits, these means taking the form of

2

either a switch or a revolving knob which is used for varying the degree of attenuation and impedance mismatch in the receiver circuit.

It is, therefore, a principal object of this invention to provide a means for controlling the sensitivity of sound-powered receivers by reducing the number of effective ampereturns in the receiver circuit, and by mismatching its impedance with respect to the impedance looking away from the receiver, the impedance of the receiver normally matching the impedance of the outgoing circuit for obtaining maximum sensitivity of the receiver when it is connected to long transmission lines.

The novel features which are believed to be characteristic of this invention are set forth with particularity in the appended claims. The invention itself, however, both as to its organization and method of operation, together with the further objects and advantages thereof, may best be understood by reference to the following description in connection with the accompanying drawings in which:

Figure 1 is a schematic diagram of a portable substation circuit of the local battery type, in which the sensitivity of the receiver is varied by altering the number of effective turns in the coil of the receiver;

Figures 2 to 5 are schematic diagrams of the receiver and balancing circuit disclosed in Fig. 1, in which the sensitivity of the receiver and mismatching of the impedances is accomplished by means of resistance elements, and

Figure 6 is an equivalent schematic diagram of the substation circuit shown in Fig. 1.

Figs. 7 and 8 illustrate two plan views of a handset and one of the methods of mounting the sensitivity-selecting switch, with the receiver and transmitter removed and a side view of the switch assembly being illustrated in Fig. 8.

Referring to Fig. 1, it discloses one of the most desirable types of substation circuits for local battery use, which is known in the United States telephone industry as U. S. Army telephone EE-8.

It includes a transmitter 10, a receiver 12, an induction coil, or an autotransformer having coils 14, 16 and 18, isolating condenser 20, a reactance balancing condenser 22, a ringer 24, a hand generator 26, a ringing circuit switch 28, a transmitter switch 30, and a receiver switch 32. Hand generator 26 is used for ringing purposes, whose cranking handle is coupled through a cam to switch 28, so as to transfer this switch to a contact 33 at the beginning of the ringing operation. Switch 28 normally rests on contact 34

which is connected to ringer 24, the circuit of which is completed through a condenser 36. The outgoing line conductors 38 and 40 are connected across the induction coil through condensers 22 and 20, and transmitter 10 is of standard, carbon type. It is connected across the primary winding 16 of the autotransformer, a local source of potential 42 supplying the necessary power for the transmitter. Parasitic discharge of source 42 where switch 30 is closed is prevented by inserting the condensers 20 and 22 in the balancing and line circuits, respectively. Transmitter switch 30 is provided for disconnecting the transmitter, and especially battery 42, from the primary winding 16 to prevent unnecessary discharge of battery through the primary when the transmitter is not in use. The secondary windings 14 and 18 of the autotransformer are connected to the conductors of the outgoing line, as mentioned previously, winding 18, in combination with condenser 20, forming a balancing network of the substation circuit, the impedance and the number of turns of this balancing network being so adjusted as to act as an anti-side-tone device during the transmitting cycle. The substation circuit disclosed in Fig. 1 may be shown in a simplified form so as to represent a balanced A. C. Wheatstone bridge as illustrated in Fig. 7, the respective components of the substation circuit being similarly numbered in both figures. As is well-known in the art, the circuit, theoretically, is designed to satisfy the conditions for no current in the receiver with an E. M. F. in the transmitter, and for no current in the balancing network 18-20 when there is an E. M. F. in the line. Actual circuits do not strictly satisfy these conditions for all of the different line conditions and frequencies, so that in actual substation circuits there is always a small current flowing in the receiver when transmitting, and a small current flowing in the balancing network when receiving. The disclosure need not be burdened with a discussion of the anti-side-tone features of the substation circuit, since it is well-known in the art, and is fully disclosed by G. A. Campbell and R. M. Foster in the "Transactions of the A. I. E. E." vol. 39, pp. 231-290. As demonstrated in the above mentioned article, the impedance of receiver 12, in order to obtain the optimum utilization of power, must be equal to the impedance of the outgoing circuit when looking from the terminals of the receiver. Accordingly, the impedance of the sound-coil of receiver 12 is equal to the equivalent impedance measured across the conductors 44 and 46 which connect the receiver to this impedance. This impedance includes the impedance of the outgoing line and the terminal apparatus on the other side of the line, if the impedance of the line is smaller than the characteristic impedance.

In the disclosed circuit the standard electromagnetic receiver has been replaced with a magnetic, sound-powered receiver, and the receiver's coil has been tapped so as to have a larger number of turns in that portion of the coil which is designated by numeral 48, and a smaller number of turns in the portion designated by numeral 50. In one particular receiver the number of turns in portion 50 is 77, and in the other portion 463. The tap is connected to a spring contact 52 of the volume control switch 32, the other end of the same coil being connected to a spring 54 of the same switch. When switch 32 rests on contact 54, the entire winding of the sound-powered receiver is connected in the substation cir-

cuit, while, when switch 32 rests on contact 52, only the lower portion 50 of the receiver's coil is effective, and, as a consequence, by operating switch 32 the sensitivity of the receiver may be controlled by selecting either one of the two available sensitivities.

Examination of Fig. 7 reveals the fact that if the impedances and the ampere turns in the autotransformer are so adjusted that the potentials appearing at points 700 and 702 of the Wheatstone bridge are equal when transmitter 10 impresses the varying direct current of predetermined frequency on primary 16 of the autotransformer, no current will flow across the winding of receiver 12. As mentioned previously, this is the case in the idealized substation circuit, and in the practical substation circuits there is a presence of some side-tone current in the receiver during the transmitting cycle. If the impedance of receiver 12 is varied, as is the case with the receiver illustrated in Fig. 1, such variation of the receiver's impedance will have no effect on the balanced condition of the substation circuit during the transmitting cycle. Accordingly, the sensitivity of the receiver may be adjusted to any desired extent without impairing the normal functioning of the anti-side-tone feature of the circuit.

During the receiving cycle the current will flow through the sound coil of the receiver 12, and, depending upon the position of key 32, either the entire coil or only a small portion of it will be included in the circuit of the receiver. This circuit, as illustrated in Fig. 1, includes conductor 49, condenser 22, conductor 46, coil 50, spring contact 52, switch 32, conductor 44, primary 16, secondary 14, and conductor 38. In the idealized circuit no current will flow through the balancing networks 18 and 20 when receiving, because of the opposing potential generated by the secondary 18. With the key in the full sensitivity position, the entire coil of the receiver is included in the previously traced circuit, and with the impedance of the receiver matching the impedance of the outgoing circuit, half of the available power will be available in the receiver itself, which is the maximum sensitivity condition obtainable.

Figs. 2 to 5 disclose additional impedance-mismatching modifications and circuits for reducing the effective number of turns in the circuit of the receiver which accomplish the sought result by means of shunt or series resistances of fixed or variable values. Only the balancing leg 18-20, condenser 15, and coil 12 of the receiver are shown in Figs. 2 to 5, since the remaining elements of the substation circuit are identical to those shown in Fig. 1, the dotted line A-A indicating the line along which Figs. 2 to 5 should be connected to the substation circuit shown in Fig. 1.

In Fig. 2 a fixed resistance element 200 is connected to key 32, and when key 32 is connected to contact 54 maximum sensitivity of the receiver is obtainable. When key 32 is connected to contact 52, the coil of the receiver 12 is connected in series with resistance 200, and, as a result, the receiver has lower sensitivity.

In Fig. 3 the same result is obtained by means of a variable rheostat 300 which, when in zero resistance position, allows the receiver to operate at its maximum ampere turn efficiency. No switching key is required in Fig. 3, and the sensitivity is adjusted by means of the rheostat arm 302.

Fig. 4 discloses an arrangement where the coil

of the receiver is shunted by means of a resistance 400, and key 402 is operated to obtain lower sensitivity of the receiver.

In Fig. 5 the same result is obtained by shunting the balancing network 18-20 by means of variable resistance 500. This resistance may be a fixed resistance with a key, if so desired.

Figs. 4 and 5 disclose identical circuits from the point of view of the effectiveness of control, except that while in Fig. 4 resistance 400 is placed in the handle of the receiver, in Fig. 5 resistance 500 is placed in the portable box including the substation circuit itself.

The disclosed control of the sensitivity of the receiver may be accomplished by replacing resistance 300 in Fig. 3 with a variometer or an inductance coil with an adjustable iron core. These modifications are not illustrated in the drawing because they are less effective in accomplishing the sought result than the illustrated circuits.

Figs. 7 and 8 illustrate a telephone handset 60 equipped with a dual sensitivity switch 61 which may be either of butterfly or knob type. Conductors 62, 63 and 64 in Fig. 8 correspond to conductor 46 and two jumpers connecting the coil to contacts 52 and 54.

While the invention has been described with reference to several particular embodiments, it will be understood that various modifications of the apparatus shown may be made within the scope of the following claims.

I claim:

1. In a substation circuit, a line, an auto-transformer having first, second and third serially connected windings, a receiver having a switch, for manually controlling the sensitivity of said receiver, said receiver being connected in series with said first and second windings and the conductors of said line, a condenser connected between said third coil and said receiver, said condenser and said third coil forming an anti-side-tone circuit serially connected transmitter and a local battery connected across said second winding and means, including said switch, for varying the number of effective ampere turns in said receiver.

2. In a substation circuit, a line, a transformer having first, second and third serially connected windings, a receiver having a volume control switch, said receiver being connected in series with said first and second windings and the conductors of said line, a condenser in serial relation with said third winding, said condenser and said third winding forming an anti-side-tone circuit connected across said receiver, a transmitter connected in shunt of said second winding of said transformer, a winding in said receiver, and means including said volume control switch for at will including all the ampere turns of said receiver winding or only a portion of said ampere turns in said receiving circuit.

3. In a substation circuit, a line, a transformer having first, second and third serially connected windings, a condenser connecting said third winding to a line conductor, said condenser and said third winding forming an anti-side-tone network of said substation circuit, a handset including a transmitter and a receiver, said receiver being connected across said network, a volume control receiver switch and a transmitter key mounted on the handle of said handset between the receiver and transmitter, a series receiving circuit including said switch, receiver, first and second windings and the conductors of said line, a series transmitter circuit including said key, trans-

mitter, and said second winding, said key providing means for at will opening and closing said transmitter circuit, and means including said switch for at will including all or only a portion of the normally available ampere turns in said receiving circuit.

4. In a substation circuit, a line, a transformer having three windings, a handset including a transmitter and a receiver, a volume control receiver switch mounted on the handle of said handset between said transmitter and receiver, a receiving circuit including said switch and receiver connected in series with a first and a second winding of said transformer and the conductors of said line, a third winding of said transformer and a condenser in serial relation connected in shunt of said receiver to form an anti-side-tone circuit, a transmitter circuit including said transmitter connected in shunt of said second winding of said transformer, a winding in said receiver, and means including said switch for including at will all or only a portion of the normally available ampere turns in said receiving circuit.

5. In a substation circuit, a line, a transformer having first, second and third windings, a condenser connecting said third winding to a line conductor, said condenser and said third winding forming an anti-side-tone network of said substation circuit, a transmitter connected across said second winding, a receiver having three terminals, a receiver winding connected between said first and third terminals, a tap connection extending from said second terminal to means for varying the number of effective ampere turns of said winding, a volume control receiver switch having connections to said second and third terminals and means for switching between said connections for including either the maximum or only a portion of the receiver's ampere turns.

6. In a substation circuit, a line, a transformer having three windings, a receiver having a winding of a plurality of turns between receiver terminals, a connection extending from one of the terminals of said receiver winding, a volume control receiver switch having means for switching between one of said receiver terminals and said connection and a receiver circuit including said switch, said switch connecting either the entire winding of said receiver or only a portion of the normally effective ampere turns of said receiver.

7. In a substation circuit, a line, a transformer having three windings and a condenser connected in series in bridge of the line conductors of said line, a transmitter connected in bridge of one of said windings, a receiver connected in bridge of said condenser and another of said windings, said receiver having a winding whose impedance matches the normal impedance of said substation circuit at the points where said receiver is connected into said substation circuit, a connection extending from a point in said receiver winding, a first receiver circuit including the entire receiver winding thereby matching the impedance of the receiver with respect to said substation circuit to secure the greatest output level from said receiver in response to incoming signals, a second receiver circuit including said connection and said receiver winding thereby mismatching the impedance of the receiver with respect to the impedance of said substation circuit to introduce a loss in the output level from said receiver in response to incoming signals of the same strength as were received in said first receiver circuit, and a switch-

ing key for switching the substation circuit at will from one of said receiver circuits to the other of said receiver circuits dependent upon the output level desired from said receiver.

8. In a substation circuit including line conductors, a transformer, a transmitter and a receiver, said receiver having a winding whose impedance matches the normal impedance of said substation circuit at the points where said receiver is connected into the substation circuit, a connection extending from a point in said receiver winding, a first receiver circuit including the entire receiver winding thereby making the impedance of the receiver with respect to said substation circuit to secure the greatest output level from said receiver in response to incoming signals, a second receiver circuit including said connection and said receiver winding thereby mismatching the impedance of the receiver circuit with respect to the impedance of said substation circuit to introduce a loss in the output level from said receiver in response to incoming signals of the same strength as were received in said first receiver circuit, and a switching key for switching the substation circuit at will from one of said receiver circuits to the other of said receiver circuits dependent upon the output level desired from said receiver.

9. In a substation circuit, an autotransformer having first, second, and third serially-connected coils; first and second condensers connected in series between a first line conductor and said first coil; a magnetic, sound-powered receiver with its winding connected across said first condenser and said first coil; a second line conductor connected to the outer terminal of said third coil whereby the receiving circuit of said substation circuit is through said second condenser, winding of the receiver, and second and third coils of said transformer, the impedance of said winding of the receiver matching the equivalent impedance looking away from said receiver; a local battery transmitter circuit connected across the second winding of said transformer, whereby said first coil and said first condenser act as an anti-side-tone circuit of said receiver, and a resistance element connectable across said anti-side-tone circuit for varying the effective ampere turns of the winding of said receiver.

10. In a substation circuit, an autotransformer having first, second and third serially-connected coils; first and second condensers connected in series between a first line conductor and said first coil; a magnetic, sound-powered receiver with its winding connected across said first condenser and said first coil; a second line conductor connected to the outer terminal of said third coil whereby the receiving circuit of said substation cir-

cuit is through said second condenser, winding of the receiver, and second and third coils of said transformer, the impedance of said winding of the receiver matching the equivalent impedance looking away from said receiver; a local battery transmitter circuit connected across the second winding of said transformer, whereby said first coil and said first condenser act as an anti-side-tone circuit of said receiver, and a resistance element connectable in series with the winding of said receiver for maintaining the effective ampere turns of the winding of said receiver substantially constant when the intensity of the signal impressed on said substation circuit exceeds the intensity of the signal normally impressed by a line having characteristic impedance.

11. A telephone handset including a receiver, a receiver circuit connected to said receiver, a transmitter, a transmitting circuit connected to said transmitter and means within said handset for varying the amount of energy applied to the receiver, and a manually operable control device on the exterior of said handset to which said means is responsive.

12. In a device of the class described, a handset including a transmitter and a receiver, a volume control device for varying the sensitivity of the receiver, said control device being mounted on said handset casing between the transmitter and the receiver; a receiving circuit, and means associated with said control device for varying the output of said receiver, said means being responsive to operation of said control device.

13. A telephone handset including a receiver equipped with a dual sensitivity control device, a receiver circuit connected thereto, a transmitter adapted to be connected to a transmitter circuit, means within the receiver circuit for causing the impedance of the receiver to match the impedance of the telephone circuit looking away from said receiver or for at will causing the impedance of the receiver to mismatch said impedance, and a manually operable switch for controlling said means whereby the level output of the receiver may be varied at will.
